(57) **CLAIM**

The ornamental design for a sealing gasket apparatus as shown and described.

DESCRIPTION

**BRIEF DESCRIPTION OF NATURE AND
INTENDED USE OF INVENTION**

The present invention is a sealing gasket used to create a fluid pressure seal in certain devices including, without limitation, valves used in offshore well intervention operations.

DESCRIPTION OF THE FIGURES

FIG. 1 depicts a front perspective view of the sealing gasket apparatus of the present invention.

FIG. 2 depicts a side view of the sealing gasket apparatus depicted in FIG. 1.

FIG. 3 depicts a rear elevation view of the sealing gasket apparatus depicted in FIGS. 1 and 2, rotated about a substantially vertical axis from the view depicted in FIG. 2.

FIG. 4 depicts a top view of the sealing gasket apparatus depicted in FIGS. 1 through 3.

FIG. 5 depicts a bottom view of the sealing gasket apparatus depicted in FIGS. 1 through 4.
